CLAIM

The ornamental design of a front panel for a keyboard
and display unit, substantially as shown.

DESCRIPTION

FIG. 1 is a front view of the front panel for a keyboard
and display unit embodying my new design.

FIG. 2 is a back view thereof, and

FIG. 3 is a right side view thereof.

The panel is shaded to indicate contrast and has a uniform
thickness throughout.

FIG.3

FIG.2

FIG.1
